[57] CLAIM

The ornamental design for a combined monitor and support, as shown and described.

DESCRIPTION

FIG. 1 is an isometric view of a combined monitor and support showing my new design;

FIG. 2 is a front elevational view of my new design;

FIG. 3 is a rear elevational view of my new design;

FIG. 4 is a right-side elevational view of my new design;

FIG. 5 is a left-side elevational view of my new design;

FIG. 6 is a top plan view of my new design; and,

FIG. 7 is a bottom plan view of my new design.

The broken lines are shown in FIG. 1 for illustrative purposes only and form no part of the claimed design.
